UNITED STATES PATENT OFFICE.

LOUIS STEINBERGER AND GUY HILL, OF BROOKLYN, NEW YORK.

INSULATED SUPPORT FOR INDUCTANCE-COILS.

1,342,308.

Specification of Letters Patent.

Patented June 1, 1920.

Original application filed August 9, 1917, Serial No. 185,370. Divided and this application filed May 18, 1918. Serial No. 235,335.

To all whom it may concern:

Be it known that we, LOUIS STEINBERGER and GUY HILL, citizens of the United States, and residents, respectively, of the borough of Brooklyn, county of Kings, city and State of New York, have jointly invented certain new and useful Improvements in Insulated Supports for Inductance-Coils, of which the following is a specification.

10 Our invention relates particularly to insulated supports for mounting inductance coils in radio apparatus.

One of the objects of our invention is to so mount the conductor forming the coil 15 that it is entirely exposed to the air except at those places where it is in metallic contact with the supporting posts or studs.

Another object is to mount the conductor in such a manner as to permit it to radiate 20 heat to a maximum degree, thereby providing for rapid self cooling of the conductor.

Another object is to so mount the coils as to produce both a maximum electrical efficiency and at the same time provide great 25 mechanical strength.

Another object is to so construct the mounting that the coil may be conveniently put in place and thereby permit of various 30 methods of mounting.

Another object is to so construct the coil and mounting therefor as to permit of a maximum ventilation and mechanical strength, and to also assemble the parts that 35 they may be easily reached for repair and at the same time guard against the loss of electrical efficiency.

Another object is to so construct the coil mounting and coil winding that the complete structure is mechanically strong and in which there are no metallic parts except those that are in electrical contact with the conductor forming the coil so that brushing to isolated metal screws and parts will be 45 prevented.

Other objects will appear hereinafter in the specification and claims.

This application is a division of our prior application Serial No. 185,370, filed August 50 9, 1917.

Referring to the drawings, in which similar characters indicate the same parts in the several views:

Figure 1 is an elevation of a structure for holding the inductance coil of helical form 55 in a vertical position.

Fig. 2 is a horizontal section on line 2—2 of Fig. 1.

Fig. 3 is an elevation of a modified construction of securing the helical inductance 60 coil in vertical position.

Fig. 4 is a horizontal section on line 4—4 of Fig. 3.

Fig. 5 is a section of an insulating supporting rod showing the pins secured there- 65 to projecting in diametrically opposite directions in staggered relation to each other.

Fig. 6 is a section of supporting rod showing pins projecting therethrough with the exposed portions opposite each other. 70

Fig. 7 is a horizontal section similar to Figs. 2 and 3 showing two helical coils, one being mounted interiorly of a skeleton supporting frame, and the other being mounted exteriorly of the skeleton supporting frame, 75 the pin supports being arranged as illustrated in either Figs. 5 or 6.

Referring to Figs. 1 and 2, we show a frame work consisting of a base 90 supporting a series of insulating rods 91 arranged 80 in a vertical position, the free upper ends are secured in any suitable way by a cap 92. Metallic studs 30 project inwardly and radially from the insulating rods, the bases of the studs being molded to the rods as shown, 85 and they are so arranged with respect to each other that a helical coil 93, consisting of a metal strip, may be wound and mounted internally of the structure with respect to the supporting rods, as shown. 90

In Figs. 3 and 4, we have shown a structure similar to that which has just been described with the exception that the metallic studs 30 are molded to the rods 91 and project radially outward from the said insulating supporting rods 91 so that the helical coil 93 may be wound and secured to the projecting metal studs 30 exteriorly of the supporting framework. 95

In both of the structures just described, 100 slots 95 are formed at the ends of the metallic pins of such shape as to receive snugly the edge of the helical coil.

In Fig. 7 we have shown a skeleton framework of insulating rods 91, supported by a 105 base 90 in a similar manner to the construc-

tion shown in Figs. 1 and 3. The insulating rods 91 are mounted upright upon the base and are provided with pins or studs 30^a molded thereto which project beyond 5 diametrically opposite sides of said uprights. These pins or studs support the helical coils 93^a and 93^b, these coils being mounted respectively on the exterior and interior of the skeleton frame formed by the 10 uprights 91.

In all of the structures above described, the metallic coils can be made in the form of a wire of any cross section, or in the form of a ribbon or tape, which is the preferred 15 form.

In Figs. 5 and 6 we have shown respectively an arrangement of metallic studs 30 and 30^a molded on the insulating supporting rods which can be used for mounting a 20 helical metallic coil upon the rods. As shown in these figures, the metallic studs are arranged to project in opposite directions but they are insulated from each other so that two coils can be mounted upon one support. 25 These constructions are of advantage in those cases where a fixed coupling is desired or a maximum inductance is required in a small space.

In Fig. 5 we have shown the metal studs 30 arranged in staggered relation to each other and in Fig. 6 the projecting ends of the studs are opposite to each other, and we have found that a convenient way to 35 mount the metal studs 30 in such a construction is to provide a stud 30^a which is longer than the thickness of the support and which penetrates the support so that the exposed ends project on both sides thereof. When the metallic studs project through 40 the insulating support, the two conducting coils which are wound and supported therebetween, one on each side of the support, are arranged in parallel so as to provide for greater current carrying capacity. The 45 metallic coils in each instance are permanently secured to the projecting studs by solder or any other suitable securing means.

In constructing our invention we may use any suitable insulating material, but we 50 have found that it is preferable to use that insulating material which is known in the art as "electrose."

Having now described our invention what we claim as new and desire to secure by Letters Patent is:

1. In a device of the class described, a support of insulating material, metallic studs having coil carrying ends, each having a supporting end molded in said support and 60 the coil carrying end projecting beyond the surface of said support, the pins being arranged in staggered relation, and projecting from opposite surfaces of said support.

2. In a device of the class described, a 65 supporting structure, rods of insulating ma-

terial carried thereby, coil carrying studs carried by said rods, and a helical conductor carried by said studs.

3. In a device of the class described, a supporting structure, a plurality of rods 70 carried by said structure and arranged equidistant from a common locus, supporting studs carried by said rods and projecting in lines extending radially from said locus and a helical coil carried by said pins. 75

4. In a device of the class described, a supporting structure, a plurality of rods carried by said structure and arranged at equal radial distances from a central point, a plurality of supporting studs carried by said rods and projecting radially in a plane extending through a vertical line containing said point, said studs on adjacent rods being spaced in helical progression, and a helical inductance coil carried by said studs. 80

5. In a device of the class described, a supporting structure, a plurality of rods carried by said structure and arranged at equal radial distances from a central point, a plurality of supporting studs carried by 90 rods and projecting radially away from a vertical line containing said point, said studs on adjacent rods being spaced in helical progression, and a helical inductance coil carried by said studs. 95

6. In a device of the class described, a supporting structure, a plurality of rods of insulating material sustained by said supporting structure, coil supporting studs carried by said rods, and a helical conductor 100 carried by said studs.

7. In a device of the class described, a supporting structure, a plurality of rods of insulating material sustained thereby, said rods being located at equal radial distances 105 from a given center line, a plurality of coil supporting studs carried by said rods projecting radially in lines extending through said center line, and a helical conductor supported by said studs. 110

8. In a device of the class described, a supporting structure, a plurality of rods of insulating material sustained thereby, said rods being located at equal radial distances from a given center line, a plurality of coil 115 supporting studs projecting radially away from said center line and a helical conductor supported thereby.

9. In a device of the class described, a supporting structure, a plurality of rods of insulating material sustained thereby at equal 120 radial distances from a center line, a plurality of studs projecting radially from said rods through said center line, said studs being spaced longitudinally along said rods to 125 accommodate a helical conductor, and a helical conductor carried by said studs.

10. In a device of the class described, a supporting structure, a plurality of rods of insulating material sustained thereby at 130

equal radial distances from a center line, a plurality of studs projecting radially from said rods away from said center line, said studs being spaced longitudinally along said 5 rods to accommodate a helical conductor, and a helical conductor carried by said studs.

11. In a device of the class described, a skeleton supporting structure comprising a 10 base, a cap and a plurality of insulating rods rigidly connecting said cap and base, a helical conductor, means carried by said insulating rods for supporting the helical conductor on the exterior of said skeleton sup- 15 porting structure.

12. In a device of the class described, a skeleton supporting structure comprising a base, a cap and a plurality of insulating rods, metallic studs molded in said rods for 20 supporting said helical conductor on the exterior of said structure.

13. In a device of the kind described, an insulating support and a plurality of op-

positely disposed independently mounted helical conductors carried thereby. 25

14. In a device of the kind described, an insulating skeleton support provided with outer and inner sides and helical conductors carried respectively upon the outer and the inner sides thereof. 30

15. In a device of the kind described, a skeleton support of insulating material provided with an outer and inner side, a series or set of metallic studs projecting from each of said sides, and a conducting coil secured 35 to each set of studs, one coil on each side of said skeleton support.

In witness whereof we have hereunto set our hands at the borough of Manhattan, city and State of New York, this eighth day 40 of May, 1918.

LOUIS STEINBERGER.
GUY HILL.

In presence of—

JOHN J. RANAGAN,
ZITA M. GRAHAM.
